ELECTRICAL DISCHARGE DEVICE AND BASE

Ward W. Watrous, Jr., Chatham, N. J., assignor
to Westinghouse Electric Corporation, East
Pittsburgh, Pa., a corporation of Pennsylvania

Application April 26, 1944, Serial No. 532,730

11 Claims. (Cl. 250—27.5)

1

This invention relates to electrical discharge devices and more particularly to a novel form of base therefor.

The principal object of my invention, generally considered, is to provide an improved form of base which is interchangeable with other forms of bases commonly used, but which includes in addition a side contact connecting with the grid or other electrode of the device, in order to avoid the necessity for the easily-broken seals sometimes used at the sides of the envelopes for electron-discharge devices.

Another object of my invention is to provide a base construction which obviates the necessity for the expensive and easily-broken seals through the side walls of envelopes for electron-discharge devices.

A further object of my invention is to provide a base which is interchangeable with those at present employed, but which has a side connection functioning as the side wall seal of the device.

A still further object of my invention is to provide a connection with the control grid of an electron-discharge device, by bringing the grid lead inside of the base, through a side wall thereof, and fastening it to a base-wall-connected cap, thereby avoiding the easily-broken side-wall seal and providing a construction in which the vacuum in the envelope is not impaired, even though breakage of the base contact terminal does occur.

Other objects and advantages of the invention, relating to the particular arrangement and construction of the various parts, will become apparent as the description proceeds.

Referring to the scale drawing:

Figure 1 is an elevational view with parts in vertical section of a thyratron embodying my invention;

Figure 2 is a bottom plan view of the device illustrated in Fig. 1;

Figure 3 is an elevational view, from a slightly different angle, of the lower portion of the device shown in Figure 1, with parts broken away to more clearly show the inner construction.

It is current practice in the construction of a number of types of electrical tubes to employ a connecting terminal on the side of the envelope, sealing a lead therefrom through the glass side wall of said envelope, as for connection with one of the electrodes such as the enclosed grid. A device of such a character is illustrated in the Livingston Patent No. 2,044,618.

There are several reasons why such a construction is undesirable. First, the expense of making a side seal, and second, such a terminal is by its very nature mechanically weak, whereby sufficient pressure or a bump easily cracks the glass envelope and ruins the device.

In accordance with my invention I propose to

2

eliminate such a side seal and the objections above discussed, at the same time making it possible to construct a new or modified tube which is applicable to sockets built for the side-seal-type of tube.

Referring to the drawing in detail, there is shown a thyratron 11 comprising a glass or vitreous envelope 12 which is evacuated and provided with a small quantity of filling material, such as mercury vapor and/or inert gas. The envelope is provided with a reentrant stem 13, through the press 14 of which extend lead wires 15 on the bottom of an attached base 16. The opposite end of the envelope is constricted and capped with a terminal member 17 which makes connection with a depending rod 18 sealed through the glass at the upper part of the constricted portion or dome 19 of the envelope, and carries a member 21 adapted to function as the anode of the device.

Opposed to the anode and suitably supported by lead-in wire 22, and wire 23 the lower end of which is embedded in press 14, is a cathode generally designated 24 which may be of any suitable construction, for example, such as described in detail and claimed in my application Ser. No. 525,659, filed March 9, 1944, now Patent No. 2,424,293, dated July 22, 1947, and owned by the assignee of the present application. A suitable heater, the lower end portion 20 only of which is shown, and the other end of which may be grounded to the cathode structure, as described in said patent, is also provided for the cathode, leads from the cathode and opposite ends of the heater therefore connecting respectively with three of the prongs 15. As illustrated in Figure 1, the prongs 15 toward the observer, left to right, are connected, respectively, to the cathode and its heater and to the other terminal of said heater, that of the other two to the left is connected to the shield grid 31 through the wire 33 and connection 40, the remaining prong being connected to the cathode by wire 23.

Between the cathode 24 and anode 21 is a control grid, generally designated 25, which is desirably of the form described and claimed in my application Ser. No. 503,598, filed September 24, 1943, now Patent No. 2,381,632, dated August 7, 1945, and owned by the assignee of the present application, that is, it has a single circular opening for the passage of electrons, said opening being desirably coaxial with the cathode and the anode. Instead of making a connection with the grid 25 through the side of the envelope 12, in accordance with the Livingston and other constructions, I carry the lead 26 from said grid through the press 14, out of an aperture 27 in the side of the base 16, and connect it to an outer contact cap 28, functioning like a side-wall con-

tact cap, as by means of spot-welding indicated at 29.

The discharge between the cathode and anode is desirably confined by shield-grid devices comprising a lower hollow cylindrical section 31 around the cathode and extending along to about the central portion of the grid 25, and an upper hollow cylindrical section 32 extending from just above the central portion of the grid 25 to a position well above the anode 21, said sections desirably being coaxial and of equal diameter. Each shield-grid section desirably has an annular transverse baffle and is otherwise constructed in accordance with my Patent No. 2,381,632, previously referred to.

The shield grid sections are desirably carried by supporting wires 33, in turn carried by a collar 30 applied to the stem 13 and clamped securely thereto. These wires project upwardly on the outside of said shield grid sections in contact with the outer surfaces, being welded or otherwise secured thereto. The wires preferably extend to the upper end of the upper section 32, but the upper end portion of each is desirably left unwelded, thereby enabling the same to be bent outwardly and carry a bead 34 to engage the envelope and brace the assembly with respect to the dome 19 of the envelope 11, in the manner described and claimed in my application Ser. No. 476,158, filed February 17, 1943, now Patent No. 2,353,775, dated July 18, 1944, and owned by the assignee of the present application. A suitable connection for the screen grid sections 31 and 32, is made between one of the support wires 33 and the remaining one of the prongs 15, in any desired manner.

The base 16 of the device illustrated is desirably formed of suitable insulating material, such as Bakelite, some other plastic, glass, or metal with insulating inserts. The lower section 35 is hollow and generally cylindrical, with its lower end closed by a lower wall 36 in which the upper portions of the prongs 15 are embedded in a conventional or suitable manner. The diameter and height of the section 35, as well as the size of the prongs 15 may be conventional, so as to interchange with electron devices having pear or other shaped envelopes with side-wall connections with the grids, like in the Livingston patent referred to, so that my improved device may interchange with such devices.

The upper portion 37 is hollow cylindrical, with its minimum internal diameter greater than the maximum external diameter of the section 35, with its inner surface, however, desirably flaring upward slightly so as to nestingly receive the lower portion of the envelope 12. The lower portion thereof is connected with the upper edge of the lower section 35 by an annular web 38, which may also be considered as an inwardly extending flange on said upper cylindrical portion 37, which is of a diameter preferably larger than that of the lower section 35. Of course, the diameter is determined by the size of the envelope, the lower portion of which it receives.

The grid cap 28, is desirably formed of brass or the like, and mounted on the strong moulded shell or base 16 which, because of its construction, is extremely difficult to break. Furthermore, if it were broken, the vacuum within the envelope would not thereby be impaired. The cap may be fastened to the side wall of said enlarged base portion 37 in any desired manner, as by the use of a self-tapping screw 39. Said portion 37 desirably has a ridge 40, or other ir-

regularity, interlocking with the correspondingly-formed edge 41 of the cap 28 to prevent undesired turning of the latter. The ridge 40, if used, provides a thickened section as part of the rim 5 of the portion 37, adapting it for the more secure reception of the screw 39 in a correspondingly threaded apertured portion of said thickened section screw, the shank of which passes through a hole in the outer wall of the cap 28 and the head 10 of which engages the preferably countersunk edge portions defining said hole.

From the foregoing disclosure it will be seen that I have provided an improved electron device having a moulded base of novel form, including an addition to the four prongs for making connection with the cathode, cathode heater terminals, and screen grid, as in my Patent No. 2,424,293, previously referred to, a side contact for the control grid. Besides securing an additional contact by this means, I also get one which has insulation resistance with respect to the bottom prongs higher than that between said bottom prongs.

Although a preferred embodiment of my invention has been disclosed, it will be understood that modifications may be made within the spirit and scope of the appended claims.

I claim:

1. A base for an electrical device comprising a hollow portion with a plurality of contact elements, a hollow generally-cylindrical portion of minimum internal diameter larger than the maximum external diameter of said first-mentioned hollow portion to receive a portion of the envelope of said device, connected to one end of said first-mentioned portion by a flat web outstanding peripherally therefrom, a contact member on said portion of larger diameter, and an aperture in said larger cylindrical portion to receive a lead to said contact member.

2. A base for an electrical discharge device comprising a hollow generally-cylindrical portion with a plurality of axially-extending prongs to fit a conventional socket, a hollow generally-cylindrical portion of minimum internal transverse section larger than the maximum external transverse section of said first-mentioned hollow portion to receive an end portion of the envelope of said device, connected to said first-mentioned portion by a flat web outstanding peripherally therefrom, and a contact member on said portion larger in transverse section.

3. A base for an electrical device molded integrally from plastic material, comprising a hollow generally-cylindrical portion closed at one end by a wall from which contact prongs extend, said prongs fitting a conventional socket, a hollow generally-cylindrical portion of correspondingly larger diameter connected to the open end 55 of said first-mentioned portion by an annular inwardly-extending end flange, said larger portion being adapted to receive an end portion of said electrical device and apertured for the passage of a lead therethrough, a contact cap, and a screw 60 passing therethrough and threadably securing it to such a larger portion adjacent said aperture in order to be secured to said lead.

4. A base for an electrical device molded integrally from plastic material and comprising, a lower hollow portion from which contact prongs project, an upper hollow portion connected to the lower portion and of larger diameter, said upper portion having a ridge thickening a part of its rim, and a hollow metal contact cap having its edge shaped to interlock with said ridge and se-

cured to said rim by a screw passing into the ridged portion thereof.

5. An electrical device comprising an evacuated envelope, electrodes therein, a heater for one of said electrodes, and a base for said device comprising; first, a hollow portion with a plurality of outwardly-projecting contact elements, respectively connecting with one of said electrodes and said heater, and second, a hollow generally-cylindrical portion of larger diameter for receiving an end portion of said envelope, said base portions being united by a flat annular flange extending between adjacent end portions thereof, and a contact member, on the side of said portion of larger diameter, connected to a lead from another of said electrodes.

6. An electrical discharge device comprising an axially elongated evacuated envelope, a cathode therein, a heater for said cathode, an anode disposed in said envelope near one end, opposite said cathode and axially spaced therefrom, a grid disposed between said cathode and anode, an outer contact at one end of said envelope and connected to said anode, and a base for said device comprising a hollow portion with a plurality of contact elements respectively connected to said cathode and heater, a hollow generally-cylindrical base portion of larger diameter for receiving the end portion of said envelope opposite to said outer contact, and a flat web extending at an angle to the sides of both base portions and uniting the adjacent ends thereof, and a contact member on the side of said portion of larger diameter and connected to a lead from said grid.

7. An electrical discharge device comprising an evacuated envelope, a cathode therein, a heater for said cathode, an anode disposed in said envelope near one end, opposite said cathode and axially spaced therefrom, a grid in said envelope disposed between said cathode and anode, an outer contact at one end of said envelope and connected to said anode, and a base comprising a hollow portion carrying a plurality of contact elements to fit a conventional socket and respectively connecting with said cathode and heater, and a base portion larger in cross-section receiving the end portion of said envelope opposite to said outer contact and connected to said first-mentioned base portion by a wall, the plane of which is transverse to the base axis, disposed adjacent to the received portion of said envelope, and a contact member on the side of said portion of larger diameter and connected to a lead from said grid.

8. An electrical discharge device comprising an axially elongated evacuated envelope, a cathode therein, a heater for said cathode, an anode disposed in said envelope near one end, opposite said cathode and axially spaced therefrom, a grid disposed between said cathode and anode, an outer contact at the upper end of said envelope and connected to said anode, and a base for said device molded integrally from plastic material and comprising a lower hollow generally cylindrical portion closed at its lower end by a wall from which contact prongs project, said prongs being formed and spaced to fit a conventional socket and connected respectively with said cathode and heater, an upper hollow generally cylindrical portion connected to the lower portion by an annular inwardly extending lower flange and of correspondingly larger diameter, the lower portion of said envelope fitting and secured to said upper generally cylindrical base portion, the latter being apertured, a lead from the grid passing there- 55

through, and a contact cap united to said lead and secured by a screw to said upper portion adjacent said aperture.

9. An electrical discharge device comprising an evacuated envelope, a cathode therein, a heater for said cathode, an anode disposed in said envelope opposite said cathode, a grid disposed between said cathode and anode, and a base for said device molded integrally from plastic material 10 and comprising a lower hollow portion from which contact prongs project and an upper hollow portion connected to the lower portion and of larger diameter, said upper portion having a thickening ridge, and a hollow contact cap having its edge correspondingly formed, interlocking with said ridge, and secured to said upper portion by a screw passing into the ridged portion thereof, and a lead from said grid passing through said upper portion and electrically connected to 20 said cap.

10. An electrical discharge device comprising an evacuated envelope, a plurality of electrodes therein, a heater for one of said electrodes, an outer contact at an upper end of said envelope 25 and connected to one electrode, and a base for said device comprising a lower hollow generally cylindrical portion closed at its lower end by a wall from which contact prongs project, said prongs being formed and spaced to fit a conventional socket and connected respectively to an electrode and the heater thereof, an upper hollow generally cylindrical portion connected to the lower portion by an annular inwardly-extending lower web and of correspondingly larger diameter, 30 the lower portion of said envelope fitting and secured to said upper generally cylindrical base portion, the latter being apertured, a lead for the remaining electrode passing therethrough, and a contact cap united to said lead and secured by 35 removable means to said upper portion adjacent said aperture.

11. An electrical discharge device comprising an evacuated envelope, a plurality of electrodes therein, a heater for one of said electrodes, and an insulating base for said device comprising a lower hollow portion from which contact prongs project and an upper hollow portion connected to said lower portion and of larger diameter, 45 said upper portion being thickened by a ridge, and a hollow conductive cap having its edge correspondingly cut out, interlocking with said ridge, and secured to said upper portion by detachable means passing into the ridge portion thereof.
